US00D622272S

(12) **United States Design Patent**
Machida et al.

(10) **Patent No.:** **US D622,272 S**
(45) **Date of Patent:** **** Aug. 24, 2010**

(54) **SCANNER**

(75) Inventors: **Takashi Machida**, Niza (JP); **Minoru Nishizawa**, Nishitokyo (JP); **Kanehiro Yoshida**, Kodaira (JP)

(73) Assignee: **Canon Denshi Kabushiki Kaisha**, Chichibu-shi, Saitama (JP)

(**) Term: **14 Years**

(21) Appl. No.: **29/346,171**

(22) Filed: **Oct. 28, 2009**

(30) **Foreign Application Priority Data**

Apr. 28, 2009 (JP) 2009-009812

(51) **LOC (9) Cl.** **14-02**

(52) **U.S. Cl.** **D14/421**

(58) **Field of Classification Search** D14/421-425; D18/55, 49, 46, 40, 36-39, 41, 44, 45, 47, D18/48, 50-54, 56; 235/462, 455, 470, 462.43, 235/482, 483; 358/474, 486, 488, 496, 497, 358/498, 452, 449, 451, 453, 1.13; 318/685, 318/696; 355/81, 75; 399/405, 367, 379, 399/380; 382/217; 715/209, 222, 226, 274; 400/613, 613.1-613.4, 690.1-690.4, 691-694

(57) **CLAIM**

The ornamental design for a scanner, as shown and described.

DESCRIPTION

FIG. 1 is a front elevation view of a scanner showing our new design;

FIG. 2 is a rear elevation view thereof;

FIG. 3 is a top plan view thereof;

FIG. 4 is a bottom view thereof;

FIG. 5 is a right side elevation view thereof;

FIG. 6 is a left side elevation view thereof;

FIG. 7 is a perspective view from the right side thereof,

FIG. 8 is a perspective view from the left side thereof,

FIG. 9 is perspective view from the right side thereof, with the placing tray lid and left side door extended; and,

FIG. 10 is perspective view from the left side thereof, with the placing tray lid and left side door extended.

1 Claim, 10 Drawing Sheets
